UNITED STATES PATENT OFFICE.

ARTHUR BATES, OF LEICESTER, ENGLAND, ASSIGNOR TO UNITED SHOE MACHINERY COMPANY, OF PATERSON, NEW JERSEY, A CORPORATION OF NEW JERSEY.

HEEL-FINISHING MACHINE.

1,122,057.

Specification of Letters Patent.

Patented Dec. 22, 1914.

Application filed October 16, 1908. Serial No. 458,091.

To all whom it may concern:

Be it known that I, ARTHUR BATES, a subject of the King of England, residing at Leicester, in the county of Leicester, England, have invented certain Improvements in Heel-Finishing Machines, of which the following description, in connection with the accompanying drawings, is a specification, like reference characters on the drawings indicating like parts in the several figures.

This invention relates to machines for use in the manufacture of boots and shoes and particularly to machines for finishing the edges or other portions of heels and soles.

An object of the invention is to provide a compact machine comprising a series of finishing members or appliances arranged in such relative position that a heel edge, for example, can be presented to said devices for surface finishing operations in proper sequence and with a minimum of travel or movement in going from operative relation to one device to operative relation to another.

Other characteristic features of the invention include the wax feeding mechanism, the wax applying roll, the arrangements for heating said roll and a novel apparatus for making local applications of wax to portions of the stock requiring special attention.

These and other features of the invention will be more fully understood from the following description of the machine in which the invention is shown as embodied and will be finally pointed out in the claims.

Figure 1 is an end elevation of the machine, Fig. 2 is a plan view, Fig. 3 is a sectional view of the wax holder, Fig. 4 is an end view of the wax supplying means and the wax applying wheel and Fig. 5 is a front view of the same partially in section. Fig. 6 is a broken-away perspective view of the wax applying roll.

The machine comprises a base or standard 2 upon which is carried the head 4 provided with bearings for the shafts carrying the several tools which, for convenience, will be described in the order in which it is contemplated that they will be used. The shaft 5, upon which a wax applying wheel 10 is mounted, carries a large pulley 6 which is driven by a belt 7 from a small pulley on a driving shaft 8 near the foot of the machine.

The wheel 10, which is shown in partial

section in Fig. 5, has a wide rim on which is formed a circumferential flange 12 against which the wax applying roll 14 is clamped by a movable flange 15 held in position by screws 16. This roll 14 is preferably formed from a tubular piece of coarse, loosely woven, tough, high ribbed fabric rolled upon itself to produce a ring-shaped member of suitable size for use in applying wax to the edge face of the style of heels being finished. The ribs 17 extend transversely of the roll as shown, and form separate rubbing surfaces between which the wax is carried.

The porous nature of the fabric of which the roll is made adapts the roll to absorb a considerable quantity of wax and its loosely woven character adapts it for readily giving off the wax to the work presented against it. The clamping flange 15 not only holds the roll in place on the wheel but also retains the fabric in its rolled-up condition.

The wheel 10 is formed with an open inner end or an annular recess in its inner or right hand face as may be seen from Fig. 5. A gas pipe 18, or other suitable burner, extends laterally into the wheel from its inner side and thus heats the roll and maintains the wax with which it is saturated in molten condition. The wheel and roll are partially surrounded and inclosed by a shield 20 which assists in maintaining the wax on the surface of the roll in heated condition.

The shield is supported from an axle or rod 22 which also forms the fulcrum for a lever 24 that has a wax receptacle or recess in its front end. This lever 24 contains bearings for a wheel 25 shaped somewhat like a spool with a peripheral or acting face adapted to embrace the roll 14 and shape or re-shape that roll if its contour has been distorted by the pressure of the work against it.

The wheel 25 dips into the wax in the wax holder and therefore has the function of transferring wax to the roll 14. The wax in the holder is maintained in molten condition by the gas flame from a burner 26. The wax holder is formed with a laterally projecting throat as shown in Fig. 5 into which pieces or sticks of unmelted wax may be fed. The side of the wax holder adjacent to the throat is cut away, as indicated at 27 in Fig. 4, to provide communication between the throat and the chamber in which the wheel 25 turns.

The wax holder and the wheel 25 normally stand in the position shown, or in 110

the relation to the roll 14 that is illustrated in the drawings, but are adapted to be moved by rocking the lever 24 into position for the wheel 25 to embrace and shape the roll and apply wax to it. This movement of the lever 24 is effected by a connection 28 with a treadle 30 and is required only at intervals when the supply of wax on the roll is impaired and needs to be replenished or 10 that the shape of the roll has become distorted so that it needs re-forming.

In using the machine, particularly for finishing cheap shoes in which pieced heels are employed, an operator frequently has 15 occasion to make local applications of wax to fill cracks between the pieced heel lifts or other imperfections in the surface of the heel. For this purpose an auxiliary wax holder 40 is supported above the wheel 10 20 in convenient position for the operator to present the heel to it whenever he finds occasion to make a local application of the wax to the heel being treated. This auxiliary wax holder has an outlet 42 communicating 25 with a valve chamber 44 in which a piston 45 is slidably mounted and normally held by spring 46 in position to prevent the wax from escaping. The piston 45 projects outwardly from the wax holder into position 30 for the operator to engage it with the shoe at the point where he desires the local application of wax. The plunger is provided with a longitudinal bore or opening which communicates through a transverse opening 35 with the guideway in which the head of the plunger works. By pressing the shoe against the plunger the latter is forced into its guideway, opening communication through the outlet 42 with the fluid wax in 40 the auxiliary holder which thus flows down the outlet 42 whereupon the molten wax flows through the opening in the plunger to the desired point on the shoe. The spring 46 returns the plunger to position for shutting off the flow of wax as soon as the shoe 45 is withdrawn. A flame from a gas pipe 48 maintains the wax in the holder in molten condition and by heating the metal parts of the holder and plunger keeps the wax passage 50 through the plunger open so that the wax flows freely therethrough when the plunger is forced into its guideway.

In front of the wax applying wheel 10 and to the right therefrom, as appears in Fig. 2, are mounted the shafts 50 which support the wax spreading rolls 52 arranged one above the other, the upper one being slightly in the rear of the lower one. The two spreading rolls are arranged with their adjacent edges in close proximity, as shown in Fig. 1, to permit the heel thrust into the angle between them to have its opposite sides acted upon simultaneously by pressing the heel rearwardly between the rolls and 60 swinging the toe end of the shoe upwardly 65

and downwardly. The tread rest 53 is placed adjacent to the angle between the spreading rolls 52 in position to be engaged by the heel during this operation. The purpose and advantages of this arrangement of the rolls 52 are more fully explained in U. S. Letters Patent No. 805,763 to C. B. Tuttle to which reference may be made. The entire edge surface of the heel can be very quickly subjected to the operation of the spreading rolls. These rolls may be of any suitable formation to adapt them for other purposes as for example—they may comprise a circular brush provided with a canvas cover. The wax spreading rolls are driven by a belt 54 which is looped over pulleys on the shafts 50 as indicated in dotted lines in Fig. 1 and extends around a relatively large pulley on the driving shaft 8 so that the spreading rolls are driven at a much higher speed than the wax applying wheel 10. It is, of course, desirable to drive the wax applying wheel at such a low speed that there will be no tendency for the molten wax to be thrown off by centrifugal force. The spreading rolls 52, however, may, with advantage, be driven much more rapidly in order that they may work the wax into the surface of the heel more quickly. The advantages resulting from applying the wax by a slow moving wheel and spreading it and working it into the surface of the stock by a rapidly rotating wheel, or wheels, much more than compensate for the use of spreading wheels for performing the second of the two operations and especially is this true when a pair of spreading wheels are employed as herein shown for spreading the wax on the two sides of the heel at the same time.

Shafts 60 for supporting wax polishing wheels 62 are arranged as shown in Fig. 2 in advance of and to the right of the wax spreading rolls. These shafts and wheels thus bear the same relation as to position to the wheels 52 that the latter wheels do to the wheel 10. The polishing wheels may comprise brushes made of soft bristles or may be of any other suitable construction for their purpose and these wheels are also arranged as described in said Tuttle patent to treat the two sides of a heel simultaneously. The polishing wheels are driven by a belt 65 looped about small pulleys on the shafts 60 and extending about a pulley 66 on the shaft 8 which is substantially larger than the pulley which drives the belt 54 and the wax spreading wheels. This arrangement gives to the polishing wheels a substantially greater speed than is given to the spreading wheels as it is found that the polishing operation can be carried on advantageously by wheels driven more rapidly than the wax spreading wheels should be driven. The further finishing device oc- 130

cupying a relation to the polishing wheels similar to the position which these wheels occupy relatively to the wax spreading wheels comprises beading and milling tools

5 70 and 71 mounted on a shaft 72 which is driven by a belt 74 from a pulley on one of the shafts 60. The beading tool 70 is fast on the shaft 72 while the milling tool is loose on the shaft. These beading and milling 10 devices will preferably be constructed and arranged as in U. S. Letters Patent No. 739,857 to H. W. Gould.

It will be understood from the foregoing description and drawings that the several 15 devices to be employed in finishing a heel are so formed and relatively arranged that an operator standing obliquely in front of a machine can, with little or no change of the position in which he stands, present the 20 shoe to all of the tools in their proper order or succession. This enables the heel finishing operation to be very rapidly carried out and the provision of pairs of wax spreading and wax polishing wheels still further accelerates the operation. Local applications of 25 wax from the auxiliary holder for filling cracks or crevices in a heel, or for other purposes, may be conveniently made either before a heel is presented to the wax applying 30 wheel or after that operation. Whenever it is desired to replenish the supply of wax on the roll 14, or whenever the roll becomes distorted or misshapen by the pressure 35 of the work against it the re-forming and wax supplying wheel 25 is lifted and pressed against the roll 14 by manipulating the treadle 30. The workman then thrusts the heel between the rapidly turning wax spreading wheels 52 guiding it against the 40 tread rest 53 and by swinging the toe end of the shoe upwardly and downwardly a few times while the heel is held pressed against the spreading rolls the frictional heat effects the spreading of the wax on the 45 two sides of the heel at the same time and gets it thoroughly worked into the surface of the heel. This having been satisfactorily accomplished the heel is thrust between the 50 polishing wheels 62 and the toe end of the shoe is swung upwardly and downwardly to subject the entire edge surface to the action of the polishing brushes. The heel is then presented to the beading and milling tools, the shoe being so positioned and 55 turned that the beading tool enters and runs about the heel in the rand crease while the milling tool rolls over the edge of the heel and forms a line of indentations adjacent to the heel seat end of the heel, thus complet-

ing in one operation and with one handling 60 of the shoe the entire heel finishing process while the operator remains in substantially one position.

It will be observed that the so called "friction wax finishing process" is by this 65 machine effected in three steps by three devices, viz. the wax applying wheel, the wax spreading and working-in wheels and the polishing wheels driven at different speeds; whereby the most effective applying, spreading, 70 and polishing of the wax is secured. It will also be noted that the wheels 52 which work the wax into the heel and evenly spread it are dependent entirely upon friction heat for maintaining in softened condition the wax with which their covers become saturated and the wax on the surface being treated. This is one reason why it is 75 advantageous to drive them much faster than it has heretofore seemed practical to 80 drive wheels which combined the functions of wax applying and wax spreading devices. No tread rest is shown with these wheels as it is often advantageous to rock the shoe laterally between these wheels and 85 entire freedom to do so is desirable.

Having explained this invention and described a preferred construction of mechanism embodying the same, I claim as new and desire to secure by Letters Patent of the 90 United States:—

1. A heel finishing machine having in combination a wax applying wheel having a yielding working surface, a wax holder, means for heating the holder to maintain 95 the wax therein in a molten condition, a wheel 25 supported by said holder adapted to run in the molten wax and having a peripheral face transversely concaved to adapt it for re-shaping the yielding face of the 100 wax applying wheel, and means for moving the wax holder and wheel 25 together from and toward the wax applying wheel during the operation of the machine.

2. A heel finishing machine having, in 105 combination, a wheel, a wax applying member comprising a spirally rolled tubular portion of ribbed fabric, and means for clamping said roll upon the periphery of said wheel.

110

In testimony whereof I have signed my name to this specification in the presence of two subscribing witnesses.

ARTHUR BATES.
